UNITED STATES PATENT OFFICE.

OLAUS C. WOLD, OF CHICAGO, ILLINOIS, ASSIGNOR TO HENRY J. THAYER
AND CHARLES H. CHANDLER, OF SAME PLACE.

AIR-BRUSH.

SPECIFICATION forming part of Letters Patent No. 595,931, dated December 21, 1897.

Application filed March 1, 1897. Serial No. 625,572. (No model.)

To all whom it may concern:

Be it known that I, OLAUS C. WOLD, a citizen of the United States, residing at Chicago, in the county of Cook and State of Illinois, have invented a certain new and useful Improvement in Air-Brushes, (Case No. 2,) of which the following is a full, clear, concise, and exact description, reference being had to the accompanying drawings, forming a part 10 of this specification.

My invention relates to artists' brushes of the type generally known as "air-brushes," in which the pigment is distributed by means of air under pressure. Such a device is illustrated in Patent No. 555,669, issued to me 15 March 3, 1896.

My present invention has for its object the simplification and improvement of the construction of the particular type of air-brush 20 illustrated in my said patent.

In my improved form of air-brush the parts are readily assembled and disassembled, their disposition and construction being such that several of said parts may be readily inter- 25 changed or removed for repair without interfering with the disposition of the remaining parts. By my improved construction a more delicate and easy manipulation of the lever mechanism is secured. In the air-brush of 30 my said patent the longitudinally movable needle which controls the flow of the pigment has frictional engagement in its bearings through a considerable portion of its length, which in course of time causes the needle to 35 be worn, whereby its uniform direction of thrust is destroyed, which results in the delicate point of the needle coming in contact with the seat of the conical passage in which the tapered end of the needle is adapted to fit and 40 through which the flow of the pigment is controlled. If the needle be enlarged considerably in cross-section, this wear may be considerably reduced.

By means of my present invention I am enabled to form the needle of as small cross-section as is desirable, since I believe it of all frictional engagement.

I will explain my invention more particularly by reference to the accompanying drawings, in which—

Figure 1 is a side elevation, partially in sec-

tion, of a brush embodying my invention. Fig. 2 is a plan view thereof. Fig. 3 is a sectional view of a nozzle of the brush. Fig. 4 is a detail view showing the needle and a portion of the mechanism immediately associated therewith. Fig. 5 is a detail view of the operating-lever. Fig. 6 is a detail view of a valve-pin entering into the construction of my improved device. Fig. 7 is a plan view of a recessed nut associated with the valve-pin.

Like letters refer to like parts throughout the different figures.

The particular construction illustrated in Fig. 3 forms no part of my present invention; 65 but in order that the application of my invention may be readily understood I have thought it well to illustrate and describe this portion of the mechanism.

The needle *a* is surrounded by a sleeve *b*, 70 whose cross-section is of square exterior contour at the portion *b'* thereof. The portion *b'* of the sleeve is threaded. A cap-screw *a'* is secured upon the portion *b'*, a set-screw *a''* being passed through the cap-screw into engagement with the needle, whereby the sleeve and needle are relatively fixed. The relative longitudinal positions of the sleeve and needle are adjusted by the set-screw *a''*.

The shell *c* is provided with two plates or 80 partitions *d* *d'*, slightly separated, and also with an end plate *e*. The plates *d* *d'* act as bearings for the forward portion of the sleeve *b*. A bearing-sleeve *f* is passed through the end plate *e* and is secured thereto by threaded 85 engagement. A cap *f'* is screwed upon a threaded extension of the bearing-sleeve *f*, said cap being provided with a central opening through which the contiguous portion of the sleeve *b* may be reciprocated.

A helical spring *g* is interposed between the adjustable cap *f'* and the enlarged portion *b''* of the sleeve *b*. This spring tends to thrust the needle toward the nozzle of the brush. The tension of the spring may be adjusted by 95 the cap *f'*.

I preferably provide an annular shoulder *f''*, which bears against the rear face of the end plate *e* when the sleeve *f* is screwed into position.

I provide a back lever *h*, which engages 100 the enlarged portion *b''* of the sleeve *b* at *b''*

and which is adapted to be turned about its lower edge by the lever *i*. The lever *i* is linked at *i'* to the knurled finger-plate *i*², which is provided with an eye *i*³, which receives a guide *i*⁴, mounted upon the end plate *e*. The guide *i*⁴ serves to confine the finger-plate to the path practically parallel with the axis of the needle. When the finger-plate is thrust rearwardly, the sleeve *b* and the needle are moved backward by the back lever *h*, the spring *g* being counteracted in this movement. The forward motion of the sleeve *b* and needle is limited by the square portion *b'* engaging with partition *d'*. The full motion of the lever-plate is not imparted to the needle, however, since the needle is nearer the fulcrum of the back lever.

By providing the link connection *i'* and engaging the lever *i* with the back lever the backward motion of the finger-plate is accompanied by a comparatively much smaller motion of the needle during the beginning of the movement of the finger-plate than was possible with the device of my aforesaid patent. I thus am enabled to govern the width of a fine spray within very close limits where a delicate adjustment is most needed. When the finger-plate is moved farther backward to produce larger sprays, the relative motion of the needle becomes much larger, as will be apparent on an inspection of the drawings, delicate adjustment being not here required. The air-brush being a very small instrument the value of these features will be appreciated.

It is desirable to have the travel of the finger-plate considerably in excess of the travel of the needle actuated thereby, since a very delicate adjustment of the needle may be had. By my construction the sleeve *b* relieves the needle of all wear. As will be observed, a considerable portion of the length of this sleeve is engaged by the containing-sleeve *f*, whereby frictional wear is greatly reduced.

A stem *k*, carrying the valve, is screwed into a boss *k'*, passing through and secured to the bottom portion of the shell *c*. Within the stem is provided a valve-pin *l*, (shown more clearly in Fig. 6,) having its upper end slotted for the reception of a pin *e*², which unites the members of the forked end of the lever *i*, the pin *e*² serving as an axis or fulcrum for said lever. The pin *l* is provided with a shoulder *l'*, which may have its upper surface faced with rubber. A coil-spring *l*³, encircling the pin *l*, normally presses the shoulder *l'* against its valve-seat, the end of the spring resting against a nut *l*⁴, screwed into the end of the stem. The nut *l*⁴, as is shown more clearly in Fig. 7, is cut away at the sides to permit the access of air.

A second stem *m* is illustrated, which has a cup-shaped cavity at its upper portion, in which is contained a cup-like portion *m'*, mounted upon a second valve-pin *m*², similar to valve-pin *l*, this valve-pin being also provided with a shoulder *m*³, which may have

its upper surface faced with rubber. When the stems *k* and *m* are coupled, the cup-like portion *m'* is depressed against the tension of spring *m*⁴, so that air under pressure may be conducted from the supply-hose *m*⁵ through a recessed nut *m*⁶, similar to nut *l*⁴, to the air-brush through openings *m*⁷ in the portion *m'*. When the stems *k* and *m* are disunited, the shoulder *m*³ is seated, whereby waste of compressed air through the hose *m*⁵ is prevented when the air-brush is not being used.

Referring to Fig. 3, the shell *c* carries in its front end an internal thread, into which the end *n'* of the head *n* is adapted to be screwed. This head carries an elongated portion or tube *n*², in the end of which is screwed the tip *o*, formed, preferably, of platinum. This tip is provided with a conical bore, into which the conical end of the needle is adapted to fit. By moving the needle *a* forward the surface of the needle may be brought into contact with the walls of the bore, thus sealing the outlet. In practice, however, it is preferable to so adjust the needle in relation to the sleeve *b* that the needle will never quite seal the outlet. By moving the needle back to a greater or less extent the passage between the needle and the bore may be adjusted as desired. An annular passage is provided between tip *o* and the interior wall of the cap *p* for the exit of air. An annular groove *n*³ is provided in the end *n'* of the head *n*, the groove communicating by a duct *n*⁴ with the air-chamber *c*⁴. Ducts *n*⁵ extend through the head *n*, thus connecting the groove *n*³ with the reservoir *p'*, provided between the head *n* and the cap *p*. Air thus passes from the chamber *c*⁴ through duct *n*⁴, groove *n*³, and ducts *n*⁵ into the reservoir *p'*, from whence it passes through an annular outlet between the stem and the end of the cap, the air thus passing in a column surrounding the outlet for the paint, thus drawing the paint from the paint-receptacle. The paint is placed within the shell and rests upon the partition *c*⁵, which separates the paint-receptacle from the air-chamber. The air enters the chamber *c*⁴ through the duct *r*, communicating with the bore of the stem *k*. The air is admitted by a downward pressure upon the lever *i*, the air finding passage to chamber *c*⁴ through the duct *r*.

In the construction hitherto employed a portion of the paint passed through the forward bearing of the needle and came in contact with and injured the operating mechanism of the brush. By providing the double partition *d*² with a slight interspace between the same the paint that is carried backward is caught between the partitions and is prevented from entering that portion of the shell *c* which contains the lever mechanism. The paint that is accumulated between the partitions becomes dry and may be readily removed by a hooked tool inserted through the hole in either partition upon removing the tube or sleeve *b*. The sleeve *b* is adapted to

reciprocate upon two separated bearings $d f$, between which the lever mechanism is interposed. The back lever engages the tube in place of engaging the needle, so that the removal of the needle from the tube for purposes of cleaning the brush, which has to be done four or five times each day, will not cause the separation of the parts of the lever mechanism.

10 It frequently becomes desirable to remove the stem k , which with the construction heretofore employed was not possible without first removing the needle, but by extending the valve-pin l above the stem k and slotting the same I free the engagement of the lever i with the stem, whereby the stem may be readily screwed into place or removed without interfering with the said lever, while at the same time the air is controlled with equal 15 facility. It will be apparent also that the needle may be readily removed with but slight trouble and without interfering with the condition of the lever mechanism or valve-pin.

Changes may be readily made in my invention without departing therefrom, and I do not therefore desire to be limited to the precise construction shown; but,

Having thus described my invention, I claim as new, and desire to secure by Letters 30 Patent, the following:

1. In an air-brush, the combination with a casing adapted to contain the paint and having an outlet therefor, of a needle for controlling the size of the outlet and thereby the flow 35 of the paint, a reciprocating finger-plate i^2 , means for guiding the same in a path practically parallel with the needle, and suitable mechanism intervening between the plate and needle for imparting longitudinal motion 40 to the needle, substantially as described.

2. In an air-brush, the combination with a needle for controlling the emission of paint from the brush, of a finger-plate i^2 , supporting an eye i^3 , a guide i^4 engaging said eye, 45 and suitable mechanism intervening between said plate and needle for imparting longitudinal motion to the needle upon the actuation of the finger-plate, substantially as described.

3. In an air-brush, the combination with a 50 casing adapted to contain the paint and having an outlet therefor, of a needle for controlling the size of the outlet and thereby the flow of the paint, a reciprocating finger-plate i^2 , means for guiding the same in a path practically parallel with the needle, a lever i fulcrumed at its lower end and linked at i' to the plate i^2 , and a back lever h fulcrumed at its lower edge and engaging lever i near the portion i' , said back lever being adapted to 55 impart longitudinal motion to the needle when actuated, substantially as described.

4. In an air-brush, the combination with a 60 casing adapted to contain the paint and having an outlet therefor, of separated bearings

d and f , a sleeve b supported by said bearings, a back lever engaging the sleeve interposed between the bearings for imparting longitudinal motion to the sleeve, said bearings serving to direct the sleeve in a uniform line of travel, and a needle removably secured to 65 said sleeve for controlling the size of the outlet and thereby the flow of the paint, whereby said needle may be withdrawn without disorganizing the mechanism, substantially as described. 75

5. In an air-brush, the combination with a casing adapted to contain the paint and having an outlet therefor, of separated bearings $d f$, a sleeve b supported by said bearings, means for imparting longitudinal motion to 80 the sleeve, said bearings serving to direct the sleeve in a uniform line of travel, and a needle removably secured to said sleeve for controlling the size of the outlet and thereby the flow of the paint, said needle being thus freed 85 from sliding contact with bearing-surfaces, substantially as described.

6. In an air-brush, the combination with a needle for controlling the emission of paint, a sleeve b secured to said needle, a bearing-sleeve f in which the sleeve b is adapted to reciprocate, a cap-screw f' upon sleeve f , a spring g tending to thrust the sleeve b and needle in one direction, and means for thrusting 90 said needle and sleeve b in the other direction, substantially as described. 95

7. In an air-brush, the combination with a casing adapted to contain the paint and having an outlet therefor, of a needle for controlling the size of the outlet and thereby the flow of the paint, a reciprocating finger-plate i^2 , means for guiding the same in a path practically parallel with the needle, a valve for regulating the admission of air under pressure to said casing, a reciprocating pin l projecting from the valve, and a lever i linked at i' at its upper end to the plate i^2 and engaging the pin l at its lower end, substantially as described. 100 105

8. In an air-brush, the combination with a casing, of separated bearings $d f$, a sleeve adapted to be longitudinally reciprocated in said bearings, a finger-plate i^2 , means for guiding the same in a path practically parallel with the needle, a back lever h engaging 110 the sleeve for imparting longitudinal motion thereto, a lever i linked at i' to the finger-plate, said back lever engaging lever i near the portion i' , a valve for controlling the admission of air to the casing, and a valve-pin 115 extending therefrom and engaging the lower end of lever i , substantially as described. 120

In witness whereof I hereunto subscribe my name this 25th day of February, A. D. 1897.

OLAUS C. WOLD.
